UNITED STATES PATENT OFFICE.

MATTHEW HENRY WHITTAKER, OF MANCHESTER, AND CHARLES HOLLIWELL, OF BROADBRAE, ENGLAND, ASSIGNEES TO LINOTYPE AND MACHINERY LIMITED, OF LONDON, ENGLAND.

TYPE BARS OR SLUGS.

1,102,458.

Specification of Letters Patent. Patented July 14, 1914.

Application filed September 27, 1913. Serial No. 792,978.

To all whom it may concern:

Be it known that we, MATTHEW HENRY WHITTAKER and CHARLES HOLLIWELL, subjects of the King of the United Kingdom of Great Britain and Ireland, and residing, respectively, at Norton House, Hornby Road, Old Trafford, Manchester, in the county of Lancaster, England, and Linotype and Machinery Works, Broadheath, in the county of Chester, England, have invented new and useful Improvements in Type Bars or Slugs, of which the following is a specification.

This invention relates to typographical line-casting machines, and to the devices known, and hereinafter referred to, as "slugs" cast therein, which bear on one edge a line of printing characters, and it has for its object to provide means for rendering the said slugs more serviceable for a certain class of work than they have heretofore been, as ordinarily constructed.

The particular class of work above referred to, is the printing of Christmas and New Year's cards and other devices or articles having printed thereon, greetings or announcements, hereinafter termed "texts", and also the sender's name and, if desirable, the address also. Frequently these devices are printed in small batches of say, a few dozen each and it often happens that orders are received from different persons requiring the same text but with different senders' names. For this reason the characters for printing the text are generally stereotyped or otherwise constructed so as to render them suitable for being permanently locked up in the chase, while the type for printing the sender's name and address, set up in the chase either in separable type or in cast slugs, are periodically changed to give effect to the changes in such names and addresses.

Difficulty has heretofore been experienced in using slugs for printing the sender's name because that name has sometimes necessitated a slug of greater measure than could be accommodated between the side sticks or furniture of the chase, and the said name sometimes occupies a length of the slug appreciably short of its full measure which latter was sufficient to extend from one to the other side of the chase, the difficulty in connection with the last-named device arising out of the fact, that, unless the name were exactly central on the slug, it could not be

centralized relatively to the text. According to the present invention, these difficulties are entirely overcome by forming the aforesaid slugs so that the edges thereof which bear the printing characters, can extend over the side sticks or furniture of the chase and so that the said slugs can be adjusted longitudinally within the chase.

The invention will be best understood by reference to the accompanying drawings in which:—

Figure 1 is an isometrical view of a slug, the printing matter on which is of shorter measure than the distance between the two sides of the chase; Fig. 2 is an isometrical perspective view of a mold capable of producing slugs such as shown in Fig. 1; Fig. 3 is an isometrical perspective view of a chase with a slug such as that illustrated in Fig. 1 locked up along with a stereotype plate and other slugs bearing the address of the senders; Fig. 4 is a representation on an enlarged scale taken from the matter set up in the chase illustrated in Fig. 3; and Fig. 5 is an isometrical perspective view of a slug on which the measure of the printing matter is such as might, to secure centralization thereof, render it desirable to be longitudinally adjusted in either direction.

The essence of the present invention may be said to reside in the formation of the name slugs 1 with their upper or printing edges 2 overhanging the feet of the said slugs either at one end, as shown in Fig. 1, or at both ends, as shown in Fig. 4, so as to render them capable of extending over the adjacent furniture 3, as shown in Fig. 3, or even over the side sticks 4 of the chase. The slugs from their feet to the printing face are of the usual type height excepting at the overhanging ends which are of such height as to admit of them extending over (conveniently without contacting with) the aforesaid furniture or side sticks.

As indicated in Fig. 3, a slug such as that indicated in Fig. 1, can be locked up in the chase 5 by the usual furniture 3, side sticks 4 and quoins 6 along with a stereotype plate 7 and other slugs 8, 8, bearing the sender's address, the said furniture being of the usual height so that the overhanging end or ends of the slug 1 can extend over it.

In the example illustrated in Figs. 1, 3 and 4, in which the senders' names are of very short measure, these names are, in the

ordinary way, cast on, or toward, one end of the slug, *viz.*—that end where no overhang is present, and when this slug is set up in the chase 5, it can readily be adjusted to centralize the printing matter thereon relatively to that appearing on the stereotype plate 7, as shown in Fig. 3.

When the sender's name is of approximately the same measure as, or of greater measure than, that of the text on the stereotype plate 7, then it might be convenient to have the slug 1 provided, as shown in Fig. 5, with an overhang at each of its ends, so that it could be adjusted in either direction with one or both of those overhangs extending over one or both of the respectively adjacent furnitures in the chase 5.

For casting a slug such as that represented in Fig. 1, the mold would be constructed preferably as shown in Fig. 2; this mold is, in general, of the construction ordinarily employed in the casting machine known commercially under the trade mark "Linotype," the only difference being that which exists in one of the end liners. This mold comprises the ordinary body 9, the ordinary cap 10 and two end liners 11, 12 all rigidly secured together, the liner 11 being recessed as at 13 for the casting therein of the overhang 14, Fig. 1, while the other liner 12 is of the ordinary construction.

For the casting of slugs such as that shown in Fig. 5, both of whose ends overhang, the liner 12 as well as the liner 11 would be recessed in the same manner as that shown in connection with the liner 11 in Fig. 2.

It is to be understood that, so far as the present invention is concerned, it is immaterial whether the characters for printing the text be on a stereotype plate as shown

in Fig. 3, a series of slugs or on separable type, the special aim of the invention being to provide slugs of such construction as admits of them being readily adjusted to secure centralization of the printing characters thereon relatively to the text. 45

Having described our invention we declare that what we claim and desire to secure by Letters Patent is:—

1. A printing form comprising printing slugs, one of said slugs being at least of the same measure as that of the others and recessed at its end below its printing surface, and the said recess being of such form and size as to permit the longitudinal adjustment 55 of the printing slug in the form.

2. A printing form comprising printing slugs, one of said slugs being at least of the same measure as that of the others and recessed at both ends below its printing surface, and the said recesses being of such 60 form and size as to permit the longitudinal adjustment of the printing slug in opposite directions in the form.

3. In a printing form, the combination of 65 the side member 3, with printing slugs one of said slugs being recessed at its end below its printing surface so as to overhang the side member, and the said recess being of such form and size as to permit the longitudinal 70 adjustment of the printing slug with reference to the side member.

In witness whereof we have hereunto set our hands in the presence of two witnesses.

MATTHEW HENRY WHITTAKER.
CHARLES ROLLIWELL.
